NONREFILLABLE BOTTLE.

Application filed October 6, 1927, Serial No. 224,418, and in Cuba September 18, 1927.

This invention relates to improvements in non-refillable bottles and has special reference to the type of non-refillable bottle shown and described in our co-pending application 5 for patent filed of even date herewith and bearing the Serial Number 224,417.

One important object of the present improvements consists in utilization of valves which are constructed of material or materials having less specific gravity than the specific gravity of water.

A second important object of the invention is to provide an improved construction of non-refillable bottle wherein certain of the 15 valves are in the form of stars with three, four, five, six or more rays or points, these valves being used for controlling the communication with the outside air.

A third important object of the invention 20 is to provide an improved disposition and construction of a certain internal cylinder used herewith which cylinder is provided with a chamber having lateral ports leading therefrom.

25 Figure 1 is an elevation view of the bottle showing the exterior appearance.

Figure 2 is a vertical diametrical section taken through the bottle and showing the arrangement of the valve down.

30 Figure 3 is an elevation of the cylinder used herewith showing the ports.

Figure 4 is a plan view of a certain star valve used herewith.

35 Figure 5 is a view of a modified form of valve arrangement employing a somewhat different construction of the internal cylinder.

In the present construction the bottle is 40 provided with a neck 10 adjacent the top whereof is a lateral flange 11 and from the periphery of this flange there extends upwardly a cylindrical wall 12 which surrounds the neck of the bottle and projects above the top thereof.

45 In the interior of this wall 12 at a point substantially level with the top of the bottle neck proper there is formed a notch 13 having an abrupt shoulder at its upper end and having its lower part inclined inwardly as 50 clearly shown in Figure 2. Fitted in the neck 10 is an outer cylinder 14 having at its top a flange 15 from which depends a skirt 16

provided with a peripheral groove 17 in which is mounted an expansion ring 18. The body of the cylinder 14 slips down inside of the 55 neck 10 with the top portion of the neck entering the space between the skirt 16 and the body of the cylinder while the spring ring 18 engages the notch 13 so that when the outer cylinder has once been inserted it cannot be 60 removed. Moreover, the top of this cylinder is slightly below the upper edge of the wall 13 thus rendering it difficult to insert a tool in such way as to pry the cylinder out.

This cylinder is open at the bottom and at 65 the top is provided with a port or vent 19 through which the liquid is poured and which may be closed by a stopper 20. Fitted within the outer cylinder is an inner cylinder having a lower part 21 and an upper part 22, the 70 lower part 21 being of greater diameter than the upper part so that a shoulder is formed between these parts and this shoulder engages a coacting shoulder formed within the outer cylinder. This inner cylinder is closed 75 at the top and the side walls of the upper part are spaced from the side walls of the exterior cylinder so as to provide an annular passage 23 between these parts of the two cylinders. The inner cylinder is hollow and the upper 80 part forms a frusto-conical chamber 24 from which leads ports 25 which afford communication between the chamber 24 and the passage 23. The upper part 22 is of such dimension that a space is left between the top 85 of the inner cylinder and the closure at the top of the outer cylinder and in this space is mounted an upper valve which consists of a plate or disc 26 having a port 27 centrally disposed to register with the port 19. The 90 disc 26 is provided with a depending flange or skirt 28 which enters the passage 23 when the disc drops thereby closing off communication from the exterior of the bottle to this passage. When the disc moves toward the 95 mouth of the bottle, as in pouring, the flange 28 will move out of the passage 23 so that a space is left between said flange and the inner cylinder and thus any liquid in the passage 23 can flow through this space and the port 27 and out of the bottle. The lower 100 part of the interior of the inner cylinder is cylindrical in form, a shoulder being formed between this lower part and the frusto-coni-

cal upper part and this shoulder is provided with slots or openings 29. Fitted in the lower part of the cylinder 21 is a valve seat 30 having a central port 40 wherein seats the conical portion 41 of a valve 42. Above this valve 42 is a star valve which consists of a cylindrical body portion 43 having upper and lower flanges provided with star points 44. These points are of such size that when the bottle is inverted for pouring they will rest on the shoulder while liquid may flow through the spaces between the points and the spaces 29. Within the frusto-conical chamber 24 is a ball 45.

15 It is to be especially noted that the valve 42 is constructed of such material as will have a specific gravity less than that of water and which will thus consequently float. It is also to be noted that the diameter of the 20 valve body 42 is less than the internal diameter of the valve wherein it is mounted so that liquid can flow around this valve when it is opened.

25 In the modified form illustrated in Figure 5 the inner cylinder has an upper wall 46 spaced from the upper part 22 so that the chamber or passage 23 is formed between this upper wall and the part 22 of the cylinder. In this form the valve 25 may be replaced by 30 a similar valve of slightly smaller diameter and in such case this valve indicated at 27 is likewise a floating valve.

35 In pouring from the bottle it will be obvious that the valve 42 will open through the weight of the water or other contents of the bottle and the bottle contents will flow out past this valve through the spaces between the points of the star and into the upper part of the inner cylinder. From there it will 40 flow through the ports 25, the passage 23 and out through the ports 26 and 19. Any attempt to pour liquid into the bottle will be prevented because with the bottle sitting upright the upper and lower valves will both be closed. Similarly if the bottle be held 45 sideways or with its axis horizontal the ball 23 will roll down the inclined side of the frusto-conical chamber and force the lower valves closed. If an attempt be made to fill the bottle while inverted the flotation of the 50 valves due to their low specific gravity will close the port or passages and thus this method of filling the bottle be prevented.

55 Obviously with this arrangement of parts it is impossible to tamper with the bottle by the introduction of a wire or the like for holding the valves open while it is refilled.

60 There has thus been provided a simple and efficient device of the kind described and for the purpose specified.

65 It is obvious that minor changes may be made in the form and construction of the invention without departing from the material spirit thereof. It is not, therefore, desired to confine the invention to the exact form

herein shown and described, but it is desired to include all such as properly come within the scope claimed.

Having thus described the invention, what is claimed as new is:

1. In a non-refillable bottle having a neck provided with a mouth end, a hollow cylinder fixed in said neck and secured against removal, said cylinder having an upper end of less diameter than the lower end and closed at said upper end, said cylinder having lateral ports in the reduced end, a ported valve seat at the lower end, a valve opening and closing said port, a star shaped valve between said valve and the upper part of said cylinder and a third valve controlling the lateral ports in said reduced end. 70

2. In a non-refillable bottle having a neck provided with a mouth end, a hollow cylinder fixed in said neck and secured against removal, said cylinder having an upper end of less diameter than the lower end and closed at said upper end, said cylinder having lateral ports in the reduced end, a ported valve seat at the lower end, a valve opening and closing 85 said port, a star shaped valve between said valve and the upper part of said cylinder, the upper part of said hollow cylinder having a frusto-conical chamber therein, a ball loosely mounted in said chamber, and a third valve 95 controlling the lateral ports in said reduced end.

3. In a non-refillable bottle having a neck provided with a mouth end, a hollow cylinder fixed in said neck and secured against removal, said cylinder having an upper end of less diameter than the lower end and closed at said upper end, said cylinder having lateral ports in the reduced end, a ported valve seat at the lower end, a valve opening and closing 100 said port, a star shaped valve between said valve and the upper part of said cylinder, the first mentioned valve being of less specific gravity than water, and a third valve 105 controlling the lateral ports in said reduced end. 110

4. In a non-refillable bottle, outwardly opening check valve means including a valve of sufficiently low specific gravity to float in water, an inner cylinder containing said valve 115 and having a reduced upper end, an outer hollow cylinder receiving the first cylinder and locked to the neck, said outer cylinder having its upper end provided with a centrally ported partition, and a valve on top of 120 said reduced end of the inner cylinder and provided with a skirt fitting around the inner cylinder in closed position.

5. In a non-refillable bottle having a neck provided with a mouth end, a hollow cylinder 125 fixed in said neck and secured against removal, said cylinder having an upper end of less diameter than the lower end and closed at said upper end, said cylinder having lateral ports in the reduced end, a ported valve seat 130

at the lower end, a valve opening and closing said port, a star shaped valve between said valve and the upper part of said cylinder, the first mentioned valve being of less specific gravity than water, an outer hollow cylinder receiving the first cylinder and locked to the neck, said outer cylinder having its upper end provided with a centrally posted parti-

tion, and a valve on top of said reduced end of the inner cylinder and provided with a skirt fitting around the inner cylinder in closed position.

In testimony whereof we affix our signatures.

JULIO JIMENEZ FERNANDEZ.
